UNITED STATES PATENT OFFICE.

JOHN BERNER, OF PHILADELPHIA, PENNSYLVANIA.

DESIGN FOR A SPONGE-CUP.

SPECIFICATION forming part of Design No. 25,660, dated June 23, 1896.

Application filed March 7, 1896. Serial No. 582,270. Term of patent 7 years.

To all whom it may concern:

Be it known that I, JOHN BERNER, a citizen of the United States, residing in the city and county of Philadelphia, State of Pennsylvania, have invented and produced a new and original Design for a Sponge-Cup, of which the following is a specification, reference being had to the accompanying drawing, forming part thereof.

10 The leading feature of my design for a sponge-cup is a body of the form of a shoe with an open toe.

The figure represents a perspective view of a sponge-cup embodying my design.

Referring to the drawing, A designates a 15 sponge-cup, the same consisting of the body B, simulating a shoe, the toe of which is open as at C.

What I claim is—

The design for a sponge-cup, substantially 20 as described and shown.

JOHN BERNER.
